PRESSER FOOT FOR SEWING MACHINES

Charles F. Rubel, Chicago, Ill., assignor to Union
Special Machine Company, Chicago, Ill., a cor-
poration of Illinois

Application February 6, 1933, Serial No. 655,521

7 Claims. (Cl. 112—235)

The invention relates to new and useful improvements in a presser foot for sewing machines, and more particularly to a presser foot used on a machine for trimming the upturned edge portions of fabric sections, turning said edge portions into flat relation to each other and joining the same by covering stitches. In an application filed by Normal V. Christensen, Harold J. Le Vesconte and Charles F. Rubel, September 9, 1932, Serial No. 632,444, there is disclosed a presser foot having a body portion with a needle opening therethrough and a slot in front of the opening adapted to receive the upturned edge portions of the fabric sections for the trimming of the same. Beneath the body portion of the presser foot are flexible fabric engaging members, one at each side of the slot. The present invention has to do with an improvement in the type of presser foot shown in this application.

An object of the invention is to provide a presser foot with yielding devices operating in front of the needle and in advance of the trimmer for controlling the edge portions of the fabric section following a cross seam or a ridge produced by an elastic attached to the fabric sections.

In the drawings which show by way of illustration one embodiment of the invention—

Figure 1 is a top plan view of a presser foot having the invention applied thereto;

Fig. 2 is a bottom plan view of the presser foot;

Fig. 3 is a perspective view of one of the yielding members with the improved yielding or auxiliary pressing member associated therewith;

Fig. 4 is a perspective view of one of the leaf depressing springs used in connection with the flexible member and which bears thereon adjacent the stitching point;

Fig. 5 is a perspective view of the leaf spring used in connection with the flexible member and bearing thereon at the front end of said member, and

Fig. 6 is a transverse sectional view through the presser foot and showing the operation of the flexible members and the auxiliary pressing members associated therewith.

The invention is directed to a presser foot for sewing machines which is especially adapted for guiding and directing fabric sections so that they may be trimmed, after which the trimmed edges are placed either in abutted relation or overlapped relation and united by stitching threads, which stitching threads not only join the edge portions but cover the raw edges of the trimmed fabric sections. The presser foot includes a shank portion which is adapted to be attached to a presser

bar in the usual manner. Rigid with the shank portion is the body portion of the foot which has a needle opening therethrough, and in advance of the needle opening is a channel or slot extending in the general direction of the feed from the front end of the foot to a point directly in front of the needle opening. This channel receives the upturned edge portions and directs the same to the horizontally disposed trimming devices. Extending along the body portion of the foot and underneath the same at each side of the channel or slot is a flexible member. These flexible members engage the fabric and cooperate in controlling the same during the feeding, trimming and stitching. The features referred to per se, form no part of the present invention, as they are shown, described and claimed in the co-pending application of Christensen, Le Vesconte and Rubel referred to above. The present invention has particularly to do with auxiliary pressing members which are associated with and cooperate with the flexible members in the holding of the fabric sections for trimming and stitching. These pressing members are located in advance of the trimmers and operate independently of the flexible members which clamp the fabric sections against the feed or the work support. The purpose of these pressing members is to hold the fabric when the flexible members are raised by a passing cross seam or elastic which has been attached to the fabric sections. The cross seam or elastic will cause the flexible members to be raised, and these auxiliary pressing members will move down into contact with the edge portions of the fabric sections, following the cross seam, and hold the same for properly positioning the edge portions for trimming.

Referring more in detail to the drawings, the presser foot consists of a body portion 1 which is attached to a presser bar 2. The body portion 1 is provided with a needle opening 3 through which the stitching needles pass. The stitch forming mechanism as illustrated is of the four-needle edge covering type disclosed in the application referred to, but it is apparent that any type of cover stitch forming mechanism may be used. The body portion of the presser foot in front of the needle opening is provided with a channel or slot 4 which receives the upturned edge portions of the fabric sections. This slot terminates in front of the needle opening and extends in the general direction of the line of feed. At the rear end of the channel or slot are the trimming devices consisting of a stationary trimming blade 5 and a movable trimming blade 55

6, which operate to trim the upturned edge portions of the fabric sections. The presser foot in rear of the trimming devices is shaped so as to turn down the edge portions for stitching, and said edge portions may be either abutted or overlapped, depending upon the construction of the presser foot and the arrangement of the trimming devices relative to the work support. The means for turning down the edge portions is illustrated 10 diagrammatically at 7.

The body portion of the presser foot is rigidly attached to the supporting shank therefor, and attached to the body portion of the presser foot and extending underneath the same are flexible 15 members 8 and 9. These flexible members extend along the channel or slot, and from the front end of the foot to the rear end thereof. The flexible member 9 is shown in perspective in Fig. 3 of the drawings. The two members are 20 similar in construction, and a description of one will answer for the other. The flexible member at the forward end thereof is bent back as indicated at 10 and is slotted as indicated at 11. At the rear end, said flexible member is bent upward- 25 ly and slotted as indicated at 12. Associated with each flexible member is an auxiliary pressing member or finger 13 which as shown in Fig. 3, is formed integral with the flexible member 9. This 30 is purely for the purpose of providing a supporting means for this auxiliary pressing member. It may be otherwise formed and supported, as it operates entirely independently of the flexible member 9. The flexible member is provided with a projecting portion 14 located directly at the 35 rear end of this auxiliary pressing member 13. Said auxiliary pressing member is bent upwardly as indicated at 15 in order to shorten the overall length of the same so as to prevent contact with the projecting portion 14 of the flexible 40 member 9. The flexible member 9 is slipped on to the forward end of the presser foot and the slot 11 placed in contact with a pin 16. The portion 12 of the flexible member 9 extends up along the rear end of the foot and straddles a lug 45 or pin 17. As noted above, the presser member 8 is similar in construction and similarly attached to the presser foot as this flexible member 9, and it also has associated therewith a similarly constructed auxiliary presser member 13^a.

The flexible member 9 is held on the presser foot by a yielding clamping plate 18. Said plate is secured to a lug projecting laterally from the body portion of the foot by means of a screw 19 which is threaded into the lug. Said plate has a raised portion and a downwardly bent end portion forming a recess 20 in the under face of the forward end thereof. When this plate is attached to the lug on the presser foot, the recess 20 engages the forwardly projecting end portion 60 of the flexible member 9 and bearing on the same will tend to hold said flexible member pressed against the under face of the presser foot. There is a similar clamping plate 18^a secured by a screw 19^a to the other side of the body portion of the presser foot which holds the flexible member 8 in place thereon.

Associated with the flexible member 9 is a leaf spring 21 which has a backturned end portion 22 adapted to be attached to the laterally projecting lug carrying the clamping plate 18. This leaf spring extends alongside of the flexible member 9 and is provided with a laterally projecting member 23 which overlies and bears on the flexible member 9 slightly in advance of the needle open-

ing. The leaf spring 21 has a projecting member 24 at the rear end thereof which freely moves in a recess in the body of the presser foot. The purpose of this leaf spring is to provide a yielding pressure against the flexible member in the region of stitching, so that when the flexible member is flexed or bent by a cross seam passing under the forward end of the foot, this leaf spring will hold the flexible member in contact with the fabric in the stitching region. The 10 same is true when the cross seam is passing from the rear end of the foot and is still flexing the member. There is a similar leaf spring 21^a associated with the flexible member 8, and said leaf spring has a laterally projecting finger 23^a which 15 operates in the same manner on the flexible member 8. The flexible members, leaf springs, and clamping plate are all similar in construction to those described in the co-pending application referred to. The present invention has to do 20 with these auxiliary pressing members 13 and 13^a which are associated with these flexible members. When one or both of the fabric sections 25 to be joined having cross seams or ribs therein extending at right angles to the edge of the 25 fabric sections, pass beneath the presser foot, the flexible members will be flexed or caused to contact with the body portion of the foot in the region of the passing cross seam. When this cross seam is passing from the forward end of 30 the foot to the trimming region, the edge portions of the fabric sections following the cross seam must be clamped and held firmly against the work support, or the feed during the stitching cycle, so as to prevent the edge portions from 35 creeping or separating, and thus forming an imperfect seam. The auxiliary pressing members will drop at once on to the edge portions of the 40 fabric sections when the cross seam leaves the same. At this time, the flexible members in advance of the cross seam are out of contact with the fabric sections, but the auxiliary pressing members will hold the fabric sections properly positioned, so that when the cross seam passes 45 the trimming devices, the edge portions will be 45 properly positioned for the continued trimming thereof. While the cross seam is passing beneath the auxiliary pressing members, they function in the same way as the flexible members and yield until they are brought into contact with 50 the body portion of the presser foot. When there are two fabric sections on one side of the foot and one only on the other, as shown in Fig. 6, this auxiliary pressing member will take a position, the same as the flexible member, so as to 55 firmly hold the fabric section of a single thickness. If the cross seam is in this single thickness of fabric, as shown in Fig. 6, the auxiliary pressing member functions in the same way, and will 60 properly clamp and hold the edge portion thereof which follows the cross seam as it passes to the trimming devices and the stitching mechanism.

It is obvious that the auxiliary pressing members may be otherwise constructed and mounted without departing from the spirit of the invention as set forth in the appended claims.

The essential feature resides in the fact that there are auxiliary pressing members located wholly in advance of the trimming devices and which can yield independently of the foot sections or of the flexible members associated therewith, for the proper clamping of the edge portions following the cross seam to the trimming devices.

Having thus described the invention, what I 75

claim as new and desire to secure by Letters Patent, is—

1. A presser foot for sewing machines comprising a body portion having a needle opening therethrough and a slot in front of the opening adapted to receive the upturned edge portions of fabric sections for the trimming of the same, said presser foot having a yieldable fabric engaging member at each side of the slot extending substantially from the front end of the presser foot to the rear end thereof, and a yielding auxiliary pressing member located at each side of said slot and extending along the same from the front of the presser foot to a point in advance of the trimming devices and operating independently of the yielding fabric engaging members for controlling the edge portions of the fabric sections in front of the trimming devices.

2. The combination of a presser foot having a body portion with a needle opening therethrough and a slot in front of the opening adapted to receive the upturned edge portions of fabric sections, trimming devices associated with the presser foot and operating to trim the upturned edge portions, said presser foot having yielding devices extending from the forward end thereof to the rear end thereof and disposed at opposite sides of the slot, and auxiliary pressing members carried by the presser foot and located along the edge portions of the slot between the forward end of the presser foot and the trimming devices and operating independently of the yielding devices for clamping and controlling the edge portions in front of the trimming devices.

3. A presser foot for sewing machines comprising a body portion having a needle opening therethrough, a slot in front of the opening adapted to receive the upturned edge portions of fabric sections for the trimming of the same, a flexible fabric engaging member at each side of the slot extending from front to rear of the foot beneath the body portion, means for supporting said flexible members so that they are free to yield independently, and an auxiliary pressing member associated with each flexible member and located between the flexible member and the edge of the slot in advance of the trimming devices for controlling the edge portions of the fabric sections.

4. A presser foot for sewing machines comprising a body portion having a needle opening therethrough, a slot in front of the opening adapted to receive the upturned edge portions of fabric sections for the trimming of the same, a flexible fabric engaging member at each side of the slot extending from front to rear of the foot beneath the body portion, means for supporting said flexible members so that they are free to yield independently, each flexible member having

formed integral therewith an auxiliary pressing member which is disposed along the edge of the slot and in advance of the trimming devices and which operates independently of the flexible member for controlling the edge portions of the fabric sections.

5. A presser foot for sewing machines comprising a body portion having a needle opening therethrough, a slot in front of the opening adapted to receive the upturned edge portions of fabric sections for the trimming of the same, a flexible fabric engaging member at each side of the slot extending from front to rear of the foot beneath the body portion, means for supporting said flexible members so that they are free to yield independently, independent spring means bearing on the flexible members in the region of stitching, each flexible member having formed integral therewith an auxiliary pressing member disposed along the edge of the slot in advance of the trimming devices and operating independently of the flexible member for controlling the edge portions of fabric sections.

6. A presser foot for sewing machines comprising a body portion having a needle opening therethrough and a slot in front of the opening adapted to receive the upturned edge portions of the fabric sections for the trimming of the same, said presser foot having a yielding fabric engaging member at each side of the slot extending substantially from the front end of the presser foot to the rear end thereof, and a yielding auxiliary pressing member at one side of said slot and extending along the same from the front of the presser foot to a point in advance of the trimming devices and operating independently of the yielding fabric engaging members for controlling the edge portion of a fabric section in front of the trimming devices.

7. A presser foot for sewing machines comprising a body portion having a needle opening therethrough and a slot in front of the opening adapted to receive the upturned edge portions of the fabric sections for the trimming of the same, said presser foot having a yielding fabric engaging member at one side of the slot extending substantially from the front end of the presser foot to the rear end thereof, and a yielding auxiliary pressing member located at the same side of the slot as said yieldable fabric engaging member and extending along said slot from the front of the presser foot to a point in advance of the trimming devices and operating independently of the yielding fabric engaging member for controlling the edge portion of the fabric section with which it contacts in front of the trimming devices.

CHARLES F. RUBEL.
